UNITED STATES PATENT OFFICE.

JAMES LAMB, OF RICHMOND, INDIANA.

RAILWAY CONSTRUCTION.

1,116,446.

Specification of Letters Patent. Patented Nov. 10, 1914.

Application filed September 1, 1914. Serial No. 859,708.

To all whom it may concern:

Be it known that I, JAMES LAMB, a citizen of the United States, residing in the city of Richmond, in the county of Wayne 5 and State of Indiana, have invented new and useful Improvements in Railway Construction, of which the following is a full, clear, and accurate specification and exposition, the same being such as will enable others 10 to make and assemble the same with exactitude.

In the operation of railways it is well known that the greatest loss of life and property and consequent expense for repairs 15 and damages results from the antique construction of the permanent way, which has not kept pace with the improvements in rolling-stock and the management of traffic. To overcome this objection and to place the 20 road-bed on par with other improvements in this line is the primal object of this invention, by the employment of which life and property will be conserved and thereby reducing the cost of railway traffic in general. 25

Further objects are to provide a road-bed for railways which will not deteriorate with time and usage; will be absolutely safe for traffic passing thereover; which can be manufactured and installed at a comparatively low price, and the maintenance of which will be practically *nil*.

More particular objects and advantages of my invention will be brought out in the 35 course of the following description, and that which is new will be correlated in the appended claims.

The preferred manner for carrying out the principles of my invention in a practical 40 way is shown in the accompanying two sheets of drawings, in which—

Figure 1 is a plan view of a portion of a completed railway constructed in accordance with my invention. Fig. 2 is a side elevation of the invention, partly in section as taken on the line 2—2 of Fig. 1. Fig. 3 is a cross section of the invention, as taken on the line 3—3 of Fig. 1. Fig. 4 is a detail section taken on an enlarged scale from that of Figs. 1 and 2, showing the manner of connecting certain parts. Fig. 5 is a detail section showing one of the clips for se-

curing the rails to the plates at points between the ties. And Fig. 6 is a perspective detail view of the upper portion of one of 55 the posts.

Similar indices denote like parts throughout the several views.

In order that the construction of my invention may be more fully understood and 60 appreciated I will now take up a detailed description thereof, in which I will set forth the invention as fully and as comprehensively as I may.

In the drawings numerals 1 and 2 denote 65 the two lines of parallel rails, which may be of the ordinary form and size. The said rails rest on cross-ties 3, 4 and 5, which I prefer should be formed comparatively small, and made of plain bars of solid steel, 70 and they may be placed a considerable distance apart, that is approximately twice the distance apart as are the ordinary ties. Located directly below the crossing of each rail with each tie is a vertically disposed 75 post, which may be of cast iron, as for instance the posts 6, 7, 8, 9 and 10, which are identical with each other. Formed on the lower end of each of said posts and projecting out laterally therefrom is a base- 80 plate 11, substantially as shown. The upper end of each post is formed bifurcated, whereby a channel is formed in the upper end of each post to receive the ties, as shown in Fig. 2. Brackets 12 and 13 extend out 85 from each side of the posts, the upper faces of said brackets being located even with and forming horizontal continuation outward of the base of said channel, thereby forming a bed for the tie, the width of the tie being 90 substantially equal to the width of said channel in the post. Formed in the upper end of the post are the two L-shaped grooves 95 14 and 15, which are oppositely disposed with relation to each other, each being parallel with and opening into the said channel, substantially as shown in Fig. 6.

Numerals 16 and 17 denote connecting plates, whose widths are the same as is the width of the base of the rails which are 100 adapted to rest thereon. The ends of each plate is bent down at right-angles thereby forming a hook, as the hook 18 shown most clearly in Fig. 6. Said hooks are adapted

to fit each in its respective groove 14—15, as denoted in Fig. 6.

Formed vertically through each bracket 12 and 13 is a bolt aperture, as indicated at 5 19 in Fig. 6, and directly outward from each of said apertures is a socket, as the socket 20 in Fig. 6.

The means for securing the rails to the ties, at each crossing thereof, comprises the 10 clips 21 and 22, which rest on the surface of the ties and extend inwardly over the base of the rails to the webs of the rails. The said clips are secured each by a bolt, 23 and 24 respectively. The said bolts being disposed through apertures 19 in the respective brackets and through corresponding apertures in the clips and the ties. Extending down from the under face of each clip is a lug, as the lug 25 shown in Fig. 4, 15 which fits in the respective sockets 20 and prevents the clips from turning out of securing position.

Connecting each rail to its plate, intermediate the ties, is a slideable clamp 26, which 25 may be placed on over the ends of the rails and plates, or the ends thereof may be bent down in contact with the base of the rail after they are located in position.

Numerals 27 and 28 denote two concrete 30 walls, made parallel with each other and located directly below the respective rails, and they extend from the plates 16—17 downward to at least even with the base plate 11, and inclosing the respective posts, substantially as shown.

Numerals 29 denotes the earth, and numeral 30 denotes the ballast.

In practice preferably two trenches are formed parallel with each other in the earth 40 29, the centers of which are the same distance apart as the distance between the centers of the rails 1 and 2. The width of each trench is wider than the width of the base of the rails thereabove. The posts, above 45 described, are then set up in said trenches and located the proper distance apart, with the base plates 11 resting on firm foundations. The ties are then placed in position extending across and resting in their channels in the upper end of the posts. The bolts 23 and 24 are then inserted upward 50 from below through their respective apertures in the brackets and the ties, which will space the posts the proper distances apart laterally. The posts on each side are then connected by the plates 16 and 17, which will place the ties the proper distances apart, and also the posts. The next operation 55 is to fill in the trenches with concrete in plastic form, extending it up to the plates 16 and 17, and thereby inclosing the posts.

Either before, or after, the placing of the concrete the rails may be placed in position on the plates and connected together by the usual fish-plates, and they may be con-

nected to the ties by the clips 21 and 22, which latter are secured by the bolts 23 and 24 as stated, whereby the rails will be securely connected to the ties. It is evident that the ties will act to connect the two walls 70 of concrete, preventing them from spreading and retaining them in proper relationship with each other. And finally the ballast 30 may be placed in position in the usual manner and extended up even with 75 or over the ties as desired.

Having now fully shown and described my invention, what I claim and desire to secure by Letters Patent of the United States, is—

80

1. The herein described railway construction, comprising a concrete formation for each line of rails, vertical posts embedded in the concrete, plates connecting the posts of each line, ties connecting the two lines 85 of posts, rails resting on each line of plates, and means for connecting the rails to the upper ends of the posts, all substantially as shown and described.

2. The herein described railway construction, comprising two parallel lines of metal posts, concrete walls inclosing the posts, metal ties connecting the posts of the two lines, metal plates connecting each line of posts, means for securing the ties to the 90 posts, means for securing the plates to the posts, rails disposed on each line of plates, and means for securing the rails to the ties, all substantially as shown and described.

3. The herein described railway construction, comprising two parallel lines of rails, ties extending across under the rails, a post extending down from the crossing of each rail and tie, means for securing the posts, the ties and the rails together, plates extending along underneath the rails and each connecting two of said posts, and concrete surrounding the posts and extending therebetween under each line of rails, all substantially as shown and described.

100

4. The herein described railway construction, comprising metal posts embedded in concrete and arranged in two lines parallel with each other, metal plates connecting each line of posts, ties extending across and each attached to posts on opposite sides, rails resting on the plates and extending parallel therewith and also resting on the ties, clips for securing the rails to the ties, and bolts connecting the clips, the ties and the posts together, all substantially as shown 115 and described.

105

5. The herein described railway construction comprising two lines of metal posts located in trenches, concrete walls filling the 120 trenches and inclosing the posts, ties secured in the upper ends of the posts each tie connecting posts of opposite lines, plates resting on the concrete walls, each plate connecting two posts of the same line, means 130

for securing the ties to the posts, rails resting on each line of plates and crossing the ties, means for securing the rails to the ties, and means for connecting the rails to plates intermediate the posts, all substantially as shown and described.

In testimony whereof I have hereunto

subscribed my name to this specification in the presence of two subscribing witnesses.

JAMES LAMB.
